Figure 1 is a perspective view, showing the front, top and left side of a band type cutoff saw unit embodying our new design;

Figure 2 is a perspective view, showing the front, top and opposite side thereof;

Figure 3 is a perspective view, looking at the rear;

Figure 4 is a perspective view of the cutoff saw unit, viewing the left side and top; and

Figure 5 is a top plan view thereof.

The sides and portion of the rear of the saw unit not shown are substantially the same in appearance as the sides and portions of the rear shown.

The dominant features of our design reside in those portions illustrated in solid lines.

We claim:

The ornamental design for a band type cutoff saw unit, as shown and described.
